UNITED STATES PATENT OFFICE.

WILLIAM JOHN EN EARL, OF MONTE VISTA, COLORADO, ASSIGNOR TO THE VACUUM CARBURETOR COMPANY, OF MONTE VISTA, COLORADO.

VACUUM-CARBURETER.

1,195,343.

Specification of Letters Patent. Patented Aug. 22, 1916.

Application filed October 23, 1915. Serial No. 57,571.

To all whom it may concern:

Be it known that I, WILLIAM J. EN EARL, a citizen of the United States, residing at Monte Vista, in the county of Rio Grande 5 and State of Colorado, have invented a new and useful Vacuum-Carburetor, of which the following is a specification.

The present invention appertains to carburetors, and aims to provide a novel and 10 improved device of that character.

One of the objects of the invention is the provision of a carburetor having an elevated fuel reservoir whereby the level of the fuel therein is above the upper end of the 15 fuel nozzle, means being provided whereby the fuel flows by gravity under all conditions into the nozzle, to assure of a uniform flow of the fuel, which will not be disturbed by the variation in the suction or flow of air 20 within the casing past the fuel nozzle.

Another object of the invention is the provision in a carburetor, of novel means for controlling the passage of air through the casing, whereby the air is first drawn past 25 the end of the fuel nozzle to effectively atomize the fuel, and in order that the increased suction will effect the admission of the air at another point so that the secondary supply of air will be drawn readily 30 into the casing, and intake manifold to be admixed with the carbureted air created by the atomizing action.

A still further object of the invention is the provision of means whereby the amount 35 of air admitted can be controlled nicely, to regulate the atomizing action, and the influx of the secondary supply of air.

With the foregoing and other objects in view which will appear as the description 40 proceeds, the invention resides in the combination and arrangement of parts and in the details of construction hereinafter described and claimed, it being understood that changes in the precise embodiment of the 45 invention herein disclosed can be made within the scope of what is claimed without departing from the spirit of the invention.

The invention is illustrated in the accompanying drawings, wherein—

Figure 1 is a vertical median section of 50 the improved carburetor showing the parts

in normal inactive position. Fig. 2 is a perspective view of one of the damper or air controlling rings and a portion of the device for rotating it. Fig. 3 is a fragmental 55 perspective view of the Venturi tube and parts carried thereby. Fig. 4 is a fragmental view of the carburetor, illustrating the means for adjusting or rotating the upper damper or air controlling ring.

In carrying out the invention, there is provided a suitable casing 1, preferably in the form of a casting, and having a vertical chamber 2 therein, the lower end of which is closed by a bottom 3 bolted or otherwise attached to the lower end of the casing or body 1. The upper end of the casing 1 is attached to the intake manifold 4 of the internal explosive engine, as usual, and the casing 1 is provided at one side 65 with an outstanding air inlet or conduit 5 adjacent the bottom 3. The inflow of air is controlled by a butterfly valve 6 carried by a spindle 7 within the conduit or inlet port 5, suitable means (not shown) being 70 employed for operating the valve 6 in the usual manner.

The bottom 3 is provided with a central 75 upwardly projecting nozzle 8, terminating between the ends of the casing, and the duct or passage 9 of the nozzle 8 extending downwardly to a depending cylinder 10 with which the bottom 3 is provided. The lower end of the cylinder 10 is closed by a screw cap 11. The liquid fuel, such as gasoline, is supplied into the cylinder 10 to flow upwardly 80 through the nozzle 8, as will presently appear.

One side of the casing 1, preferably that 85 side opposite the intake conduit 5, is provided with an outstanding fuel reservoir or chamber 12, the bottom of which is disposed in a horizontal plane adjacent or 90 slightly above the upper end of the nozzle 8, whereby the level of the fuel within the reservoir 12 will be above the upper end of the nozzle. The casing 1 and bottom 3 thereof are provided with a passage or duct 14 95 extending from the bottom of the reservoir 12 to the upper portion of the cylinder 10.

- whereby the fuel may flow from the reservoir 12 by gravity into the cylinder 10.
- In order to supply the fuel to the tank 12, the bottom of the tank is provided with a depending nipple 15 to which a coupling 16 is connected, whereby a pipe or tube (not shown) leading to a liquid fuel tank (not shown), can be connected to the coupling 16 to supply the fuel to the reservoir 12.
- 10 The coupling 16 has internal valve seat 17, and contains a ball valve 18 seatable upon the seat 17 to provide a check valve for preventing the retrograde or backward flow of the fuel from the reservoir.
- 15 The admission of fuel into the reservoir 12 is controlled by a float 21, there being a vertical valve stem 19 upon which the annular float 21 is slidable or movable, and the lower end of the stem 19 having a needle valve 20 coöperable with the upper end of the nipple 15 for controlling the inlet of fuel into the reservoir. Levers 22 are fulcrumed to the top plate 13 of the reservoir 12, and their remote arms bear upon the float 21, while their adjacent arms engage a grooved collar 23 secured to the stem 19 adjacent its upper end, whereby when the float rises due to the rising of the liquid fuel level within the reservoir 12, the float 25 will bear against the levers 22, and said levers being swung, will force the valve stem 19 downwardly to seat the valve 20. This prevents the further inlet of fuel into the reservoir but as the fuel passes from the reservoir through the passage 14 into the nozzle 8, the level of the fuel being lowered, will allow the float 21 to drop, and this releases the levers 22, so that the valve 20 can be raised by the pressure of the fuel. The 30 float controlled valve thus assures of a normal fuel level within the reservoir 12, according to prevailing practice. The top plate or cover 13 of the reservoir has a socket 24 in which the upper end of the stem or rod 19 is slidable, to steady said stem.
- A salient feature of the invention resides in the provision of means whereby the suction within the chamber 2 will not materially or appreciably affect the flow of fuel, the fuel flowing by gravity only from the reservoir through the nozzle, for which purpose the reservoir is elevated above the nozzle. Said means embodies a passage or duct 35 25 provided in the casing 1 between the chamber 2 and reservoir 12, and communicating at one end with the upper portion of the reservoir 12, and at its other end with the chamber 2 at the upper end of the nozzle 8. The passage 25 extends through the bottom 3 and upwardly through the nozzle 8 adjacent the passage or bore 9, and terminates at the end of the nozzle 8, whereby the suction in the chamber 2 will be communicated through the passage 25 into the air space within the reservoir 12 above the fuel. Thus, the suction above and below the level of the fuel within the reservoir 12 is equalized, so that the fuel will flow solely by gravity into the fuel nozzle 8. This assures of a steady flow of the fuel at all times, regardless of the variation in the suction of carbureted air into the cylinders of the engine.
- 70 Disposed for vertical movement within the chamber 2 surrounding the nozzle 8 is a vertical cylindrical sleeve 27 having an apertured bottom 28 slidably embracing the nozzle 8. The bottom 28 has an aperture through which the nozzle 8 projects, but the said bottom is otherwise imperforate. The bottom 28 of the sleeve 27 is normally disposed adjacent the bottom 3 of the casing. The sleeve 27 is provided with an annular or peripheral series of ports 29 adjacent the bottom 28, and with a second annular or peripheral series of ports 30 between its ends and above the ports 29.
- 75 Disposed within the sleeve 27 is an inverted funnel-shaped air tube 31 which has its rim attached to the sleeve 27 between the ports 29 and 30, and which has its smaller portion surrounding and spaced slightly from the upper end portion of the fuel nozzle 8.
- 80 A diametrical cross bar 32 is attached in any suitable manner to the upper end of the sleeve 27 so as to bridge or span the sleeve above the nozzle 8, and the ends of the bar 32 protrude beyond the sleeve and fit slidably within diametrically opposite vertical grooves 33 with which the casing 1 is provided, so that the sleeve will be guided for vertical movement, and will be prevented from rotating. A depending valve 85 90 95 100 105 110 115 120 125 130 34 has its upper or butt end attached to the intermediate portion of the bar 32, and projects downwardly into the passage or duct 9 of the nozzle 8.
- The valve 34 has a shoulder 35 seatable upon the upper end of the nozzle 8 to close the passage thereof ordinarily, when the sleeve 27 is in its lowermost position, which it assumes due to the gravitation thereof. The smaller or lower end of the valve 34 is provided with a stem 36 projecting downwardly within and out of the passage 9 into the cylinder 10, and a disk or piston 37 is attached to the lower end of the stem 36 and works snugly within the cylinder 10, said disk or piston having a plurality of restricted apertures 38. The piston 37 in working within the cylinder 10 provides a dash pot to prevent the too sudden or vibratory movement of the sleeve 27 and the air tube and needle valve attached thereto. This prevents the fluctuation of the air controlling means, which would naturally be objectionable, but allows the air controlling means to be operated gradually and

smoothly, since the liquid fuel within the cylinder 10 can flow at a uniform rate through the apertures 38, either when the piston 37 is being moved upwardly or downwardly, due to the similar movement of the sleeve 37. The shoulder 35 of the valve 34 in seating upon the upper end of the nozzle 8 limits the downward movement of the valve and parts attached thereto.

- 10 The influx of air through the ports 29 is controlled by an annular damper or air controlling ring 39 which snugly surrounds the lower portion of the sleeve 37 around the ports 29. The ring 39 seats upon the bottom 3, and is provided with a lower annular or peripheral series of apertures 40 which are always below the bottom 28 of the sleeve 27, and which are arranged adjacent the bottom 3 of the casing. The ring 39 has a 20 second annular or peripheral series of openings or ports 41 which are above the ports 29, or between the ports 29 and 30, so as to be normally closed by the sleeve 27, while the ports 29 are normally closed by the ring 25 39. The influx of air through the openings 30 is controlled by a second annular damper or air controlling ring 42 which snugly embraces the sleeve 27 adjacent its upper end, and which seats upon the lower ring 39. 30 The ring 42 has an annular or peripheral series of ports 43 above the ports 30, said ring 42 normally closing the ports 30, and the sleeve 27 normally closing the ports 43. The upper edge of the ring 42 rotatably engages the casing 1, and the sleeve 27 is disposed slidably within the rings 39-42. When the sleeve 27 has gravitated to normal lowered position, the ports 30 are spaced farther from the ports 43, than the ports 29 40 are spaced from the ports 41, so that when the sleeve 27 is raised, the ports 29 will start to register with the ports 41, before the ports 30 reach the ports 43. The casing 1 is provided with an annular space 44 surrounding 45 the rings 39 and 42, whereby the air can flow from the intake port or duct 5 into the space 44 completely around the rings 39-42 so as to flow through all of the ports 41-43.
- Means are provided for rotating or adjusting the rings 39-42 to bring their ports into and more or less out of alignment with the ports of the sleeve 27, to control the amount of air admitted through said ports. Thus, a pair of transverse shafts 45 are 55 journaled in any suitable manner through the casing 1 tangentially relative to the respective rings 39-42, and worms 46 are secured upon said shafts 45 within the space 44, and mesh with toothed or slotted portions 47 of the rings 39-42, whereby when the shafts 45 are rotated, the rings 39-42 will be rotated. The protruding ends of the shafts 45 are provided with knobs 48, whereby said shafts can be rotated conveniently by hand outside of the carbureter.

When it is desired to control one or both of the shafts 45 from the dash (not shown) of the motor vehicle using the carbureter, the shafts 45 are slid, to rotate the rings instead of depending upon the rotation of the shafts 45. It is evident that when the worms 46 are slid, the rings will be rotated, the same as if the worms were rotated. Thus, as illustrated in Fig. 4, each of the knobs is provided with an annular groove 49, and a rotatable shaft 50 extending to the dash (not shown) is journaled within a bearing 51 with which the casing 1 is provided, there being one of the shafts 50 for each ring 39-42. The lower end of the shaft 50 has a pin 52 projecting therefrom at an eccentric point, and said pin 52 works within the groove 49, so that by oscillating or turning the shaft 50, the pin 52 will be moved longitudinally of the shaft 45 to slide said shaft and thus turn the respective ring. When the ports of the rings are brought into alignment with the ports of the sleeve, the sleeve in being raised will permit a maximum amount of air to flow through the ports, but if the ports of the rings are brought between the ports of the sleeve, a minimum amount of air is admitted. Thus, by regulating the rings 39-42, the inflow of air can be controlled to a 95 nicety.

In operation, when the carbureter is idle, the sleeve 27 gravitates and the valve 34 loses the end of the nozzle 8, to prevent the flow of fuel into the chamber 2. The sleeve 27 also closes the ports 41-43. Now, when the engine is started to create suction within the chamber 2, the suction will draw the air tube 31 upwardly, air being admitted under the bottom 28 of the sleeve 27 through the apertures 40, to allow the air tube to be drawn upward easily. When the air tube is raised sufficiently to bring the upper ends of the ports 29 above the lower ends of the ports 41, air will be admitted through the ports 41-29 under the air tube 31, and will be drawn upwardly through said air tube past the free end of the fuel nozzle 8. At the same time that the sleeve 27 is raised, the valve 34 is raised to allow the fuel to flow from the fuel nozzle, and the air will thus atomize the fuel, to provide the carbureted air which will pass upwardly through the manifold 4 to the cylinders. The primary supply of air, therefore, will pass under and through the air tube to facilitate the atomization of the fuel, but if the suction is increased, the ports 30 are brought into communication with the ports 43, to admit a secondary supply of air, which does not pass into the air tube, but which will pass upwardly to be admixed with the carbureted air, to provide the final mixture which passes into the manifold. The rings 39-42 can be rotated 120 125 129

to control the primary and secondary supplies of air, as desired, and it will be evident that the dash pot will prevent the vibration of the sleeve 27, and that the passage or duct 25 will insure the supply of fuel by gravity from the reservoir 12 into the nozzle 8 irrespective of the suction created.

A salient feature of the invention resulting from the two passages extending from the nozzle to the upper and lower portions of the reservoir, is the fact that the suction will extend through said passages, whereby the creation of a partial vacuum in the 10 reservoir will draw the fuel from the supply tank (not shown), even though said tank be at a lower level than the reservoir. It is therefore not necessary to force the fuel by pressure from the tank into the 15 reservoir, even though the tank is lower than the reservoir, and if the tank is higher up, the flow of fuel will be assisted by gravity. The fuel will thus flow to the carburetor under all conditions, even when the 20 automobile is traveling upon a steep hill, and without the necessity of special provision being made for forcing the fuel under pressure from the tank to the reservoir. There is no liability of the carburetor being flooded with fuel, and there 25 is only a small quantity of fuel in the carburetor ordinarily.

Having thus described the invention, what is claimed as new is:

25 1. A carburetor embodying an upright casing having an atomizing chamber, an upwardly projecting fuel nozzle therein, and an outstanding elevated fuel reservoir at one side wall, said side wall having a pair 30 of vertical passages, one communicating with the lower portion of the reservoir and the other communicating with the upper portion of said reservoir, said nozzle having a pair of passages extending from the upper 35 end of the nozzle to its lower end, and the bottom of the casing having passages connecting the respective first mentioned and second mentioned passages, a float controlled inlet means for said reservoir to maintain the 40 fuel level above the nozzle, a valve seatable upon the upper end of the nozzle to close the respective passage which communicates with the lower portion of the reservoir, and means connected to said valve and disposed 45 within the atomizing chamber whereby the air suction unseats the valve.

50 2. In a carburetor, a fuel nozzle, a slideable sleeve having an air tube therein coöperating with said nozzle, said sleeve having ports below said tube, and a damper snugly surrounding said sleeve and having ports above the aforesaid ports and with which they register when said tube is moved by the suction.

55 3. In a carburetor, a fuel nozzle, a slideable

sleeve having an air tube therein surrounding said nozzle, said sleeve having ports above and below said tube, and damper means snugly embracing said sleeve, and having ports above the aforesaid ports and with which they register when said tube is raised. 70

4. In a carburetor, an upstanding fuel nozzle, a vertically slideable sleeve, an inverted funnel-shaped air tube having its rim attached to said sleeve and having its smaller portion surrounding said nozzle, said sleeve having ports above and below the rim of said tube, and damper means snugly embracing said sleeve and having 75 upper and lower ports above the respective aforesaid ports and with which they are adapted to register when said sleeve is raised, the lower ports of the damper means and sleeve registering before the others. 80 85

5. In a carburetor, a fuel nozzle, a slideable sleeve having an air tube therein coöperating with said nozzle, said sleeve having an annular series of ports below said tube, and a rotatable ring snugly embracing said sleeve 90 and having an annular series of ports above the aforesaid ports and with which they register when said sleeve is raised.

6. In a carburetor, an upstanding fuel nozzle, a vertically movable sleeve having an air tube therein coöperating with said nozzle, said sleeve having an annular series of ports above said tube, and a rotatable ring snugly embracing said sleeve and having an annular series of ports above the aforesaid 95 ports and with which they register when said sleeve is raised. 100

7. In a carburetor, an upstanding fuel nozzle, a vertically slideable sleeve having an air tube therein coöperating with said nozzle, said sleeve having annular series of ports above and below said tube, and a pair of independently rotatable rings disposed one above the other and snugly embracing said sleeve, said rings having annular series 105 of ports above the respective aforesaid ports. 110

8. A carburetor embodying a casing having an upstanding fuel nozzle, a pair of independently rotatable rings within the casing and disposed one above the other, a vertically slideable sleeve within said rings having a bottom slideable upon said nozzle, the lower ring having apertures below said bottom, an inverted funnel-shaped air tube having its rim secured to said sleeve and having 120 its smaller portion surrounding the said nozzle, said sleeve having annular series of ports above and below said rim of said tube, said rings having annular series of ports above the respective ports of said sleeve, the 125 lower ports of the sleeve registering with the ports of the lower ring before the upper ports of the sleeve register with the ports of the upper ring, means for rotating each of said rings, a cross bar carried by the 130

upper end of the sleeve and engaging the casing to guide the sleeve for vertical non-rotatable movement, and a depending needle valve carried by said bar coöperable with the 5 end of said nozzle, the casing having an annular air space surrounding the said rings.

In testimony that I claim the foregoing

as my own, I have hereto affixed my signature in the presence of two witnesses.

WILLIAM JOHN BEN EARL.
